US00D982009S

(12) United States Design Patent (10) Patent No.: US D982,009 S
(45) Date of Patent: * Mar. 28, 2023

(54) PORTABLE MONITOR

(71) Applicant: Shenzhen G-world Technology Incorporated Company, Shenzhen (CN)

(72) Inventor: Yi Lu, Shenzhen (CN)

() Term: 15 Years

(21) Appl. No.: 29/813,128

(22) Filed: Oct. 27, 2021

(51) LOC (14) Cl. 14-02

(52) U.S. Cl.

USPC D14/374

(58) Field of Classification Search

USPC ..... D14/126, 305, 307, 335–337, 339–340, D14/371–372, 374–386, 448, 451–452, D14/315–319, 345, 373–374; D24/160, D24/186; D20/20, 42; D6/300, 310 CPC .. H05K 5/0217; H05K 5/0204; G06F 1/1601; G06F 1/1641; G06F 1/1654; G06F 1/1647

CLAIM

The ornamental design for a portable monitor, as shown and described.

DESCRIPTION

FIG. 1 is a front perspective view of a portable monitor showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The broken lines in the drawings depict portions of the portable monitor that form no part of the claimed design.

1 Claim, 8 Drawing Sheets
